ATTORNEY

UNITED STATES PATENT OFFICE.

HOMER E. GILLAND, OF GRAND RAPIDS, MICHIGAN.

LOCK.

Application filed January 18, 1921. Serial No. 438,160.

To all whom it may concern:

Be it known that I, HOMER E. GILLAND, citizen of the United States of America, residing at Grand Rapids, in the county of 5 Kent and State of Michigan, have invented new and useful Improvements in Locks, of which the following is a specification.

This invention relates to locks for automobiles and has for an object the provision 10 of means for locking the hood of a vehicle against unauthorized opening when the engine is not running or when the vehicle is left unattended.

Another object of the invention is the 15 provision of a lock for this purpose which is controlled by the ignition circuit of the engine, so that when the circuit is broken and the engine idle, the hood will be locked and tampering with the mechanism beneath 20 the hood prevented.

Other objects and advantages of the invention will appear as the following description is read in connection with the accompanying drawings.

25 In the drawings:—

Figure 1 is a fragmentary section through a portion of the frame and hood of an automobile with the invention applied.

Figure 2 is an enlarged vertical section 30 through the lock and hasp, showing the same in locked position.

Fig. 3 is a similar view with the parts in unlocked position.

Fig. 4 is a rear elevation of the lock.

Figure 5 is a detail elevation of the hasp.

Fig. 6 is a front elevation of a modified form of the invention.

Referring to the drawings in detail, wherein like characters of reference denote 40 corresponding parts, the reference character 10 indicates a stationary portion of the vehicle structure, such as one of the side members of the frame and 11 one of the hinged sides of the hood.

The invention which is designed to be secured to a stationary portion of the vehicle 45 comprises a casing 12, having a chamber 13 and oppositely extending outwardly disposed apertured ears 14 which provide 50 means for securing the casing in position. The casing is further provided with a slot 16, which is designed to receive a right angled extension 17 of a hasp 18. This hasp

is secured to the hood through the medium of suitable fastening devices which pass 55 through openings 19 while extension 17 is provided with an opening 20.

Located within the chamber 13 is an electromagnet 21, the latter being secured in position by means of a bracket 22 and being 60 included in the ignition circuit of the engine, part of said circuit being indicated at 23.

The upper end of the casing 12 is provided with parallel openings 24 and 25 and mounted for sliding movement in these openings 65 are the parallel legs of a U-shaped shackle 26. One leg of this shackle operates within the opening 24 and is normally urged upward by means of a coiled spring 27. The other leg of the shackle is shorter than the 70 first mentioned leg and operates in the opening 25 and its extremity is beveled as indicated at 26'. This extremity normally projects into the slot 16 so that the hasp 18 may be inserted in this slot and during such 75 insertion will depress the shackle against the action of the spring 27 until the opening 20 registers with the opening 25, whereupon the spring will force the short arm of the shackle into the opening 20 when the parts 80 will be in locked position.

The shackle 26 has secured thereto an armature 28 and when the ignition circuit is completed to start the engine the magnet 21 will be energized and the armature 85 attracted. This will draw the shackle downward and disengage its arm from the hasp 18 and permit the hood to be opened. One or more of these locks may be applied upon 90 opposite sides of the hood as desired.

In Figure 6 there is illustrated a modified form of the invention in which the shackle is controlled by an ordinary spring lock 29, operated by a suitable key, the opening for which is indicated by the numeral 30. 95 Passing through the plate 21 which is provided with attaching ears 32, there is a lock casing 33 which houses the lock for operating the shackle 34 which passes through slots from the upper part of the casing. 100 This slotted portion of the casing is identical to the construction of the preferred form.

The invention is susceptible of various changes in its form, proportions and minor 105 details of construction, and the right is

herein reserved to make such changes as properly fall within the scope of the appended claim.

Having described the invention what is claimed is:—

The combination of a motor driven vehicle and the hood thereof, of a casing suitably secured to a stationary portion of the motor vehicle in juxtaposition to the side edge 10 of the hood and being provided with a chamber and having a slot arranged directly above the chamber and in communication

therewith by means of a pair of parallel openings, an apertured hasp carried by the side edges of the hood and being adapted to 15 be received in the slot with one of its apertures registering with an opening in the casing, a U-shaped spring pressed shackle slidably mounted in the openings of the casing and means secured in the chamber for influencing the movement of the shackle as and for the purpose specified.

In testimony whereof I affix my signature.
HOMER E. GILLAND.
